UNITED STATES PATENT OFFICE

111,094

DESIGN FOR A WRENCH OR SIMILAR ARTICLE

Joseph M. Vallone, Buffalo, N. Y., assignor to
Barcalo Manufacturing Company, Buffalo,
N. Y.

Application June 19, 1937, Serial No. 69,911

Term of patent 14 years

To all whom it may concern:

Be it known that I, Joseph M. Vallone, a citizen of the United States, residing at Buffalo, Erie County, State of New York, have invented a new, original, and ornamental Design for a Wrench or Similar Article, of which the following is a specification, reference being had to the accompanying drawing, forming a part thereof.

In said drawing:

Fig. 1 is a side view of a wrench showing my design.

Fig. 2 is an edge view thereof.

Fig. 3 is a sectional view showing the cross sectional shape of the wrench shank or handle.

The dominant feature of my design resides in the plain, unbroken central panels on opposite faces of the shank portion of a wrench of the type shown, each panel extending approximately the full length of the shank, and like the shank, being tapered from its widest middle portion toward the opposite ends of the wrench.

I claim:

The ornamental design for a wrench or similar article, substantially as shown and described.

JOSEPH M. VALLONE.
